UNITED STATES PATENT OFFICE.

GUSTAF WM. PAULSON, OF BOSTON, MASSACHUSETTS, ASSIGNOR OF ONE-HALF TO RUDOLF PAULSON, OF CAMBRIDGE, MASSACHUSETTS.

AUTOMATIC PLAYER.

No. 894,899.

Specification of Letters Patent.

Patented Aug. 4, 1908.

Application filed November 2, 1906. Serial No. 341,755.

To all whom it may concern:

Be it known that I, GUSTAF WM. PAULSON, of Boston, in the county of Suffolk and State of Massachusetts, have invented certain new and useful Improvements in Automatic Players, of which the following is a specification.

This invention relates to automatic players.

More particularly, it relates to improvements in apparatus for playing automatically instruments having a key-board like a piano, especially those operated pneumatically.

It comprises features of novelty in a number of details and in the arrangement and combination of the various details and parts 15 as hereinafter set forth.

The objects of the invention are to provide apparatus of the class described which can be installed in an upright piano casing of the sort now commonly furnished with non-automatic playing pianos, thus enabling owners as well as makers of such pianos to apply the apparatus as an attachment to pianos already made in a simple and relatively inexpensive manner, the parts being inclosed within the 25 casing.

The details of the invention will appear from the following description and from the accompanying drawings, which represent an embodiment of the invention.

- 30 In the drawings Figure 1 represents a vertical cross-section of an ordinary pianoforte embodying the invention. Fig. 2 is a front view of the same partly broken away. Fig. 3 is a sectional plan view corresponding to line 3—3 of Fig. 1, in which the ordinary pedal mechanism is omitted. Fig. 4 is a front elevation of the valve chambers, being broken away in successive planes from right to left, corresponding to lines A A, B B, C C, 35 and D D of Fig. 5. Fig. 5 is an enlarged cross-sectional view of one of the valve chambers as shown in Fig. 1. Fig. 6 is a partial plan view of some of the valve rods. Fig. 7 is an enlarged detail showing the loud 40 pedal mechanism, as in Fig. 2. Fig. 8 is a sectional elevation of the tempo and rewind valve box taken on line 8—8 of Fig. 2. Figs. 9 and 10 are other sectional views of the same on line 9—9 and 10—10 of Fig. 8. Fig. 50 11 is an enlarged view of the music rolls, and operating mechanism, similar to Fig. 12. Fig. 12 is a sectional elevation of the same taken on line 12—12 of Fig. 11. Figs. 13, 14, 15 and 16 show an alternative arrangement of

the expression valves and four different positions thereof.

Referring to the drawings: The piano casting and frame consist of the usual back K, top L, front M, key-bed N, wires P, and contains the usual mechanism Q adapted to be 60 operated by the various keys R in the ordinary manner. Within the casing I mount the necessary apparatus to manipulate said mechanism Q automatically by pneumatic means.

65 One feature of the invention relates to the construction of the keys R, which I prefer to arrange so that they will not be depressed when the instrument is automatically operated. For this purpose I divide the rear portion of each key R as shown at r, Fig. 1, and hinge the two parts together at r'. The arrangement is clearly shown in Fig. 1. When the keys are played by hand the hinge r' is inoperative, and the rod 14 which operates 70 the piano action is raised in the ordinary manner by depressing a key R. When played automatically the action comes through hammer 43, as hereinafter described, and lifts the hinged part of the key, 75 thus operating the piano action through rod 14 without moving the forward part of the keys R. By this means the felts which support the keys remain with their initial softness and are not hardened by any amount of 80 mechanical operation of the piano.

85 The music roll 15 and take-up spool 16 are mounted in compartments 17 and 18 of box 19. They are adapted to convey the music sheet 20 transferably over a series of apertures 21 in the abutment or tracker board 22 in a well known manner. The motor 23, of usual construction, is mounted opposite box 19 and serves to transfer the music sheet 20 through the agency of mechanism to be described. From apertures 21 flexible tubes 25, one for each key to be operated, furnish 90 pneumatic connection with the interconnected chambers 26, 27, 28, arranged in superposed position beneath key-bed N. These 95 are open to each other at each end through channels 29, 30, and they connect through suitable valve-boxes 31, 32, 33 and 34 to air chamber 35, whence tubes 36 and 37 lead to exhausters 38 and 39, located within the 100 lower portion of the piano casing, and operated by foot levers 40, 41.

105 The general operation will be briefly de-

scribed, after which the mechanism will be taken up in detail.

When foot levers 40, 41 are operated, air is drawn from tubes 25 and valve chambers 26, 27 and 28, creating practically a vacuum therein. As music sheet 20 is slowly transferred from roll 15 to take-up spool 16, through the agency of motor 23, (which is pneumatically connected to the vacuum system by pipe 42) some of the apertures 21 are successively or simultaneously uncovered by the usual perforations in music sheet 20. This releases the vacuum in each corresponding tube 25, operating corresponding puppet valves mounted in conjunction with valve chambers 26, 27 and 28, thereby causing the corresponding hammers 43 to operate the mechanism Q as though the corresponding key R had been depressed.

20 An important feature of the invention relates to the simplification and condensation of the key-operating mechanism.

Referring to Figs. 1, 2, 4 and 5,—valve chambers 26, 27 and 28 are divided near the middle by walls 45, so that the right half exhausts through channel 29 and the left half through channel 30. Thus, a more even vacuum is maintained and all the notes are struck with more nearly uniform force.

30 Describing one of the units, each tube 25 ends in a separate vestibule 50 (see Fig. 5) which is individual to each tube but is connected to the common valve chamber 26 by a pin-hole 51. Pin-hole 51 serves to exhaust rapidly the slight amount of air which is within tube 25, but is not large enough to appreciably affect the vacuum in chamber 26 when aperture 21 is uncovered. A larger opening 52 between chambers 50 and 26 is covered by a flexible covering 53, to which is fastened the lower end of valve stem 54, carrying two puppet valves 55 and 56. Puppet valve 55 serves to close port 57 and puppet valve 56 controls port 58. A guide bar 59 holds stem 54 in central position. Between ports 57 and 58 is a side outlet 60 connecting to a secondary individual diaphragm chamber 61, whose opening to valve chamber 26 is covered by the flexible diaphragm 62. Diaphragm 62 is reinforced by a stiff plate 63 to compel uniform action and prevent buckling. Underneath each plate 63 and slidably journaled in the bottom wall of valve chamber 26 is a striking pin 64, positioned to engage the inner end of a pivoted lever 65, whose outer end carries a vertical rod 66 slidably journaled in key-bed N and provided at its upper end with the padded hammer 43.

Fig. 5 shows my preferred form of pivoting levers 65 so that any one can be removed without disturbing the rest. Each lever has for a pivot a short pin 215, held in place by screws 216, 216.

The individual tubes 25 lead to individual 65 vestibules or pockets 50 in the valve cham-

bers 26, 27, 28, as shown in Figs. 2 and 4, which latter are common to all the keys, and through them they control individual chambers 61, each of which is connected with one of said common valve-chambers by a port 57. 70

When the vacuum in tube 25 (see Fig. 5) is opened to the atmosphere through the agency of perforated paper or music sheet 20, diaphragm 53 distends upwardly, causing puppet valve 55 to close port 57 and puppet valve 56 to open port 58, thus cutting out the secondary diaphragm chamber 61 from the vacuum system and opening it to the atmosphere, whereby its vacuum is instantly released. This release distends downwardly 80 diaphragm 62, causing striking pin 64 to descend and depress the inner end of lever 65, thereby raising the outer end of same and causing hammer 43 to raise the hinged inner end of key R and operate the mechanism Q, 85 as before mentioned. This arrangement of a common vacuum chamber with a series of adjacent individual chambers, having a pneumatic connection directly to the vacuum chamber and a mechanical connection directly to the piano action, contributes greatly to the simplicity of construction and accuracy and delicacy of performance of the apparatus. When the perforation in music sheet 20 has passed the aperture 21, a vacuum 95 is quickly reformed in vestibule 50 by means of pin-hole 51, whereupon stem 54 falls, opening port 57 and closing port 58. The vacuum in chamber 61 is thus reformed, whereupon the weight of the various parts causes the outer end of lever 65 to descend again, raising the inner end and pin 64 and completing the restoration of positions illustrated in Fig. 5.

To equalize the pulsating effect upon the main vacuum in air chamber 35 caused by the action of foot levers 40, 41, I provide storage reservoirs 70, 71, preferably mounted upon exhausters 38, 39 and controlled by valves 72, 73. Air is first drawn through tubes 36 and 37 to reservoirs 70, 71 and thence to exhausters 38 and 39.

The springs 212, 212, control exhausters 38 and 39; and springs 213, 213 control reservoir bellows 70 and 71. 115

Attention is, however, called to the relatively small capacity of the valve chambers and connecting passages, as compared with those employed in previously-constructed instruments, especially valve chambers 26, 27 and 28. All passages are large enough for easy flow of air, but by the construction here shown it is possible by a single, forceful motion on the pedals to emphasize a particular note. This responsiveness is due to the elimination of capacity from the vacuum system. The operation of these parts is further improved by arranging the exhausters to operate upon a vertical axis, which is set in the corner of the piano casing, while the 125

reservoirs 70, 71 operate upon vertical axes set nearer the center of the piano. By this means the two combine to utilize the available space completely without sacrificing the efficiency or size of either. The linkage connecting exhausters 38 and 39 to foot levers 40, 41 is illustrated in Figs. 1, 2 and 3, and consists of ball-end links 75, 76, arranged at opposite ends of levers 77, 78 pivotally mounted in standards 79, 79, 79. The lower ends of foot levers 40, 41 are pivotally supported upon a floor rest 80, which is adapted to be raised from the floor when not in use. To accomplish this, I connect the fulcrum 81 by a link 82 to a second fulcrum 83 within the piano casing, and hang to fulcrum 81 a pawl 84 which normally rests upon the floor of said casing. When foot rest 80 is raised the notch 85 in pawl 84 engages the front edge of the casing and locks the foot levers in raised position.

Referring to Figs. 1, 2, 11 and 12, the mechanism for operating music-sheet 20 is thus described. The motor 23 is of ordinary construction, and its shaft 90 is provided at its inner end with a sprocket wheel 91 rigidly secured thereto. Sprocket wheel 91 is connected by chain 92 to a second wheel 93, rigidly mounted on a sliding shaft 94, slidably mounted in box 19 and bearing 95. Upon the opposite end of shaft 94 is slidably and rotatably mounted another sprocket wheel 96, from which a chain 97 runs to an adjustable idler sprocket wheel 98 mounted on box 19, the outer side of said chain on its return engaging sprocket wheel 99, rigidly mounted on the shaft 100 which turns the music roll 15. Intermediate between these two sprocket chains 92 and 97 is a third chain 101 connecting a sprocket wheel 102, also slidably and rotatably mounted on shaft 104 which operates take-up spool 16. Sprockets 96 and 102 are each held against sliding with shaft 94 by yokes 105 and 106 respectively, which leave them free to rotate. On their opposed faces are mounted pins 107, 108 positioned for engagement respectively by pins 109, 110 on collar 111 rigidly secured to shaft 94. Between sprockets 102 and 93 is a shift collar 112 secured to shaft 94 and operated by shift lever 113 pivotally mounted at 114 upon brace 24, and adapted at its lower end to be engaged by rod 115 to cause winding or unwinding of music-sheet 20, as desired.

It is necessary to keep a certain tension upon music-sheet 20 when playing to insure good contact against apertures 21, and for securing this I provide a brake, in the form of an arm 116 pivoted to brace 24 at 117 and normally held against the face of sprocket 96 by spring 118. When rod 115 operates to cause rewinding of music-sheet 20, a button 119, at its end, releases said brake action by holding arm 116 away from said sprocket 96.

The adjustability of sprocket 98 is shown

in Fig. 12 and consists of a plate 120 in which sprocket 98 is journaled, the outer end of said plate being secured to box 19 by screw 121 and intermediate screw 122 in slot 123.

In addition to the ordinary spring sockets 136, 137, at the left ends of music roll 15 and take-up spool 16, I provide adjusting means for regulating laterally the position of music-sheet 20. For this purpose threaded socket pieces 138, 139 are screwed into the right-hand side wall of box 19, and have check nuts 140, 140 for locking the socket pieces in any desired position. These socket pieces 138, 139 carry their respective shafts 100 and 104, which are bored at their inner ends and perforated to receive the spindles of music roll 15 and take-up spool 16 and locking pins 141, 141.

In Fig. 11 the parts are shown not in operation by reason of the fact that collar 111 is midway between sprockets 96 and 102. When rod 115 is moved to the right, shift lever 113 causes collar 111 to move to the right and engage its pin 110 with pin 108 on sprocket 102. The motor 23 being in operation, take-up spool 16 is caused to revolve and wind on it the music-sheet 20, causing the instrument to play. When rod 115 is moved to its extreme left-hand position, collar 111 moves to the left and its pin 109 engages pin 107 on sprocket 96, causing music roll to revolve in the opposite direction for rewinding music-sheet 20 at the conclusion of the playing operation.

During the rewind it is desirable to accomplish two things: first, to cut out the valve chambers 26, 27 and 28 to prevent playing; and second, to speed up the motor to accelerate the operation. Also, during the playing it is desirable to vary the "tempo" as well as to vary the volume of sound in ways different from what is accomplished by the ordinary soft and loud pedal mechanism. I provide two series of valve boxes for controlling the vacuum in the various tubes, as follows: Referring to Figs. 2, 8, 9 and 10, 145 is a valve box containing two valves 146 and 147 separated by a semi-partition 148. Valve 146 controls the "tempo" and is arranged to reciprocate over a narrow elongated opening 149 in the floor of box 145. Valve 147 controls the "rewind" and is adapted to close or open the aperture 150. Beneath each opening 149 and 150 are separate chambers 151 and 152 respectively, the former communicating by means of aperture 154 with a small controlling bellows 153, having a control spring 214 (Fig. 9); and the latter communicating with bellows 153 by means of opening 155, and also with main air chamber 35 by means of tube 156. Pipe 42, before referred to, connects motor 23 with valve box 145. During the playing operation, valve 147 covers aperture 150 and valve 146 is manipulated to uncover so much of

opening 149 as is necessary to give the desired "tempo", it being well known that the faster air is withdrawn from motor 23 the faster it will operate, correspondingly increasing the speed of music-sheet 20. Air is drawn from motor 23, through pipe 42, to valve box 145, thence by opening 149 to chamber 151 and bellows 153, thence through aperture 155 to chamber 152, tube 156, to main air chamber 35. The to and fro action of the regulating bellows 153 is familiar to those skilled in the art, and needs no further explanation. During "rewind" valve 147 is open, allowing the air from motor 23 to bypass bellows 153, thus insuring quicker action. At each extremity of air chamber 35 is mounted a pair of valve boxes previously referred to as 31, 32, 33 and 34. Valve boxes 31 and 33 each contain a simple slide valve 160 for opening and closing apertures 161 to cut in and out valve chambers 26, 27, and 28 with the exhaust system during playing and "rewind" respectively. Valve boxes 32 and 34 communicate with air chamber 35 through openings 164, 164 and regulating bellows 165, 165; and also through ports 167, 168 controlled by expression valves 162, 163. These regulating bellows 165 are used during ordinary playing. I have arranged the valves 162 and 163 so that it is possible by a single control lever, as hereinafter described, to produce a loud treble with a softened bass, or the reverse, or to make both treble and bass loud or both soft. In the position shown in Fig. 4 both treble and bass are loud, both bellows 165 being by-passed. If valves 162 and 163 are drawn toward each other one stage both ports 167, 168, will be closed, throwing the air through both bellows 165 and making both treble and bass soft. Drawn another stage closer together, port 167 opens, port 168 remaining closed. This gives soft treble and loud bass. The next stage closes port 167 and opens 168, giving soft bass and loud treble. In the above arrangement, valve 162 is in two parts, separated on the valve rod by the width of the port.

An alternative arrangement, in which each valve is a single block, is shown in Figs. 13, 14, 15 and 16, which represent successive positions. Each valve has sufficient lap to cover its port in two positions, and one has a lead over the other. Thus, in Fig. 13, both ports are open, the piano playing loud. In the next stage, Fig. 14, the lead of valve 163' over 162' has closed its port 168, port 167 remaining open. In the next stage, Fig. 15, the lap of valve 163' maintains port 168 closed, although 167 is also closed; and in the fourth stage, Fig. 16, the lead of 163' has opened port 168 while the lap of valve 162' maintains port 167 still closed.

Within the casing is mechanism for operating the so-called loud pedal without using

the feet. For this purpose I provide two levers 170 and 171 both pivoted loosely at 172 on a bracket 173 secured to the piano casing. See Figs. 2 and 7. Lever 170 is positioned so that its free end extends beneath the paddle 174 of the bent rod 175. Its free end receives loosely the pin 176 fixed to the upper end of the ordinary loud pedal rod 177. Positioned on lever 170 and between pivot 172 and paddle 174 is a threaded screw 178 adapted to receive adjustably the blow of a lug 179 on the side of lever 171. To the lower end of lever 171 is attached a cord or wire leading to a bent lever 180 pivoted in key-bed N and provided with a handle 181 in front of the keys R. Rocking lever 180 by means of handle 181 causes lug 179 to strike screw 178 and raise lever 170, and by this means rock bent rod 175 so that it shall simultaneously move all the mufflers 182 away from the strings. Rod 177 is meanwhile stationary, lever 170 merely sliding upon pin 176. When the pedal 87 is depressed, lever 170 is raised by rod 177 in the ordinary manner, in which case screw 90 178 merely moves away from lug 179.

To operate the various valves in boxes 145, 31, 32, 33 and 34 I provide a series of bent levers 183, 184, 185, all pivotally mounted in key-bed N and provided with handles 186, 187, 188 respectively.

Handle 186 operates the gear shifter, the valve 147 and valves 160, 160 to change the direction of the rolling of music-sheet 20, to cut in or out the valve chambers 26, 27 and 28 and to by-pass bellows 153 for the rewind. Rod 115 is connected to the upper end of lever 190 pivoted at 191 to the casing (see Fig. 2) and having its lower end connected to lever 183 by a rod 192. Valve stem 193 leads from valve 147 and is also connected to lever 183. Valve stems 194, 194 lead from the valves 160, 160 to a cross-lever 195 pivoted at 196 to air box 35 (see Figs. 4 and 6). The inner end of lever 195 is connected by rod 197 to a pivoted lever 198, whose upper end is connected to lever 183 by another link 199. Moving handle 186 to the left will close valve 147, open valves 160, 160 and cause engagement of pins 108 and 110 (Fig. 11) setting the playing mechanism in motion. Moving handle 186 to the right will reverse the motion of the music-sheet 20, open valve 147 to by-pass bellows 153, thereby speeding up the motor, and close valves 160, 160 to cut out valve chambers 26, 27 and 28.

Lever 188 controls the tempo by means of rod 200 connected to valve 146. Linkage 201 attached to lever 188 moves an indicator 202 across a graduated scale 203 to note the desired change. Fig. 2.

The expression lever 184 operates valve stems 205, 205 attached to valves 162, 163 in much the same manner as valves 160, 160

are operated. Cross-lever 206, pivoted at 207 to air box 35 has its inner end engaged by the forked end of pivoted lever 208, which is connected to lever 184 by a link 209. See Figs. 2, 4 and 6.

The space here shown as occupied by the music roll, motor and related parts has not heretofore been considered convenient for that use, so far as I am aware, owing to the necessity of access to the piano strings for tuning, rendering it impracticable. Braces 24, 24 unite box 19 and motor 23 as a single unit, and assist in providing a simple means for temporarily removing these parts when the instrument is to be tuned, thus eliminating all the trouble ordinarily incidental to separating the connecting tubes and pipes for that operation. Pivots mounted upon box 19 and motor 23 near their upper edges are two hook-arms 125, 126 adapted to engage headed pins 127 on brackets 128 secured to the piano casing. Near the lower edges of box 19 and motor 23 are two braces 129, 130, both rigidly secured at their inner ends to the piano frame and at their outer ends adapted to receive pivot pins 131, 132 mounted respectively in box 19 and motor 23. Brace 129 has a projecting shoulder 133 to engage a pin 134 in box 19 to limit the tilting movement when hooks 125, 126 are disengaged from pins 127. Depending beneath box 19 is a U-shaped bracket 135 for supporting the various tubes 25. This being located close to the axis about which the box swings when turned outward, practically no displacement or withdrawal of the flexible tubes 25 is effected by the outward movement of their upper ends.

While the invention has been here described as applied to apparatus working at subatmospheric pressure, such being considered preferable, it is obvious that the invention might be applied to apparatus working above atmospheric pressure, using compressed air instead of a vacuum; and in the claims the chambers, which have hereinbefore been described as having the air exhausted from them, are referred to as "power" chambers, meaning by this term to cover either form of power. The specific method of applying the invention may be varied in other respects from that here shown, as will be readily understood by those skilled in the art.

One advantage of using the exhaust system is seen in the very compact and simple arrangement of the valve or power chambers which this arrangement permits. Thus, the striking pin or rod 64 may pass loosely through its aperture, and under ordinary conditions, when the same is inactive, said aperture is easily packed tight against air by an external pad 49, which is seated against the exterior of the power chamber, both by the weight of mechanism transmitted through the rod 66 and lever 65 and by at-

mospheric pressure acting against the vacuum within; while when said pin is depressed, the pneumatic being in action, the amount of air which leaks through is readily cared for by the main exhaust power. When not in action the exterior pad serves as a stop to limit the upward travel of pin 64, and thus limit the stress on the diaphragms 62. Another feature of value in this construction is the economy of space it affords by allowing the diaphragms 62 to be retracted into their respective individual chambers while in action, thus affording freer passage and reducing the requirements as to size of the valve or power chambers 26, 27 and 28.

Attention is particularly called to the simple and inexpensive construction of the valve chambers 26 and the adjacent power pneumatics, ports and valves. Thus, referring to Figs. 4 and 5, it will be seen that the top of each valve chamber 26, 27 and 28 may consist of a single board, in which there are a series of recesses 61, the whole covered over with a single strip of leather 62, while the passage 60 and the ports 57, 58 are made simply by boring two holes in the same board.

As explained above, the exterior disk 49 constitutes a pad to pack the aperture through which striking pin 64 passes, thus maintaining the chamber tight at all pins which are inactive. The chamber may be made equally tight when the pins are active by placing a pad 47 on the inner head 48 of rod 64 of suitable thickness to seat against the inside of the chamber when the pneumatic is expanded; and this constitutes a stop to limit the stress on the diaphragm 62 in the downward direction.

Claims:

1. A pneumatic action, comprising a power chamber, in combination with a series of individual power pneumatics, each having a flexible actuating wall between it and the power chamber, and also having a port to the power chamber and a port to the atmosphere; a tracker board; ducts thence; each having a flexible partition separating it from the power chamber and a pin-hole connection thereto; and valves for said ports, actuated by fluctuation of said partitions.

2. A pneumatic action, comprising a power chamber; a series of individual power pneumatics arranged on one wall thereof and expansible into the chamber; and rods piercing a closed portion of the opposite wall of the chamber, movable endwise therethrough in the line of action of said pneumatics, and exterior mechanism engaging said rods.

3. A pneumatic action, comprising a power chamber having individual recesses interiorly in one wall thereof, and a flexible diaphragm partition for each, forming power pneumatics; there being an extension of each recess within the wall, and passages

through the wall transversely intersecting each extension and forming ports therefrom to the chamber and to the atmosphere; valves for said ports, and means to operate 5 the same.

4. A pneumatic action, comprising a power chamber; a tracker board; ducts therefrom, each communicating with the power chamber by a pin-hole and separated 10 therefrom by a flexible diaphragm; a power pneumatic, separated from the power chamber by a flexible partition and connected by a port, and also having a port to the atmosphere; said ports being controlled by means 15 movable by the flexible diaphragm; and a connection from said flexible partition to the mechanism that is to be operated.

5. A pneumatic action, comprising a power chamber having a wall containing 20 within itself power pneumatics and ports therefrom to the chamber and to the atmosphere; exterior mechanism; and power transmission rods engaging the power pneu-

matics within the chamber, having bearings in a wall of the chamber, and engaging said 25 mechanism outside the chamber; with valves for said ports and operating means therefor.

6. A pneumatic action comprising a power chamber having a wall containing a series of recesses, diaphragms separating 30 them from the chamber and ports connecting them individually to the chamber and to the atmosphere; valves therefor; exterior mechanism; and power transmission rods engaging the diaphragms within the chamber, 35 having slide bearings in the opposite wall, and engaging said mechanism outside the chamber.

In testimony whereof I have affixed my signature, in presence of two witnesses, at 40 Boston October 27th 1906.

GUSTAF WM. PAULSON.
